(57) **CLAIM**

The ornamental design for a surface cleaner, as shown and described.

DESCRIPTION

FIG. 1 is an upper perspective view of the surface cleaner showing my design.

FIG. 2 is a front elevation view thereof;

FIG. 3 is a back elevation view thereof;

FIG. 4 is a top plan view thereof;

FIG. 5 is a bottom view thereof;

FIG. 6 is a side elevation view thereof; and,

FIG. 7 is an opposite side elevation view thereof.

The surface cleaner is a hand-held appliance for cleaning smooth surfaces in the home, including but not limited to glass windows, kitchen counters, and bathroom counters.
